7 Claims. (Cl. 208—240)

This invention is concerned with improvements in or relating to the desulfurization of hydrocarbon oils and more particularly to the desulfurization of heavy hydrocarbon oils.

It has been known to treat hydrocarbon fractions with oxidants of various kinds followed by removal of the oxidation products by acid washing, solvent extraction, fractional distillation, extractive distillation, or a combination of such methods such that desulfurization is accomplished by loss of the hydrocarbon portions of the sulfur bearing molecules and result in low yields of treated product.

The present invention provides a new and improved process for reducing the sulfur content of heavy hydrocarbon oils without the concomitant loss of valuable hydrocarbon oils. In accordance with the present invention, a heavy petroleum oil is treated with an oxidant to form compounds containing both oxygen and sulfur and then oil containing these compounds is subjected to a thermal treatment to rupture the sulfur-carbon bond, volatile sulfur compounds and a heavy hydrocarbon oil of low sulfur content are thereby produced with little loss of product.

The present invention is therefore particularly advantageous when applied to the treatment of hydrocarbon oils in which many of the molecules contain a sulfur atom. A further advantage of the present invention is that it can be applied to sulfur containing heavy hydrocarbon oils for which catalytic hydrodesulfurization processes (as may be employed for the desulfurization of lighter hydrocarbon oils, for example gasolines, kerosenes, light fuel oils, lubricating oils, transformer oils) are either too costly or are unsuited to the particular sulfur compounds contained in the heavy hydrocarbon oil.

It is believed that the sulfur-carbon bonds of the sulfur containing molecules are weakened by the formation of oxidation products thereof and are ruptured by thermal treatment at temperatures insufficient to degrade the hydrocarbons present in the oil.

Preferably, the oxidative treatment should be sufficient to form sulfones without further oxidation to sulfonic acid derivatives. The presence of such acid derivatives may be disadvantageous during the thermal after treatment due to sulfuric acid formation and resultant sludge and coke formation.

By heavy hydrocarbon oil, it is meant a hydrocarbon oil of which at least 50% by volume boils above 250° C. The present invention is particularly applicable to sulfur-containing hydrocarbon oils of which at least 90% by volume boils above 300° C. Examples of hydrocarbon oils to which the present invention may be usefully applied are cracked gas oils, residual fuel oils, topped or reduced crudes, crude petroleum from which the lighter fractions are absent, vacuum residues, residues from cracking processes, oils from tar sands and oil shale. The invention is especially applicable to such of these and other like materials as cannot be deeply flashed without extensive carry over of sulfur containing compounds.

Exemplary of oxidizing agents that have been found suitable for use in the present invention are the organic peracids, e.g., performic or peracetic acid or mixtures of

2

hydrogen peroxide with formic or acetic acids. Other suitable oxidizing agents are organic hydroperoxides, inorganic peracids and salts thereof, aqueous hypochlorite solutions, nitrogen peroxide or air.

Particularly suitable oxidizing agents however are mixtures of hydrogen peroxide and lower alkyl mono carboxylic acids having from 1 to 2 carbon atoms, preferably formic acid, since such mixtures appear to be selective for sulfone formation and the thermal treatment of oils thus oxidized enables the total sulfur content of the heavy oils to be reduced significantly. It has been found that particularly satisfactory proportions of reactants to use in the oxidizing step are those where the molar ratio of acid to peroxide is less than 4:1 and greater than 1:10, preferably from about 1:1 to about 1:5. At the higher ratios of acid to peroxide, the by-product formation during the thermal after-treatment tends to increase, whereas at the lower ratios the degree of desulfurization achieved is less satisfactory. It is preferred that the molar ratio of peroxide employed to the sulfur present be greater than 1, and further it has been found that no significant increase in desulfurization is achieved using a molar ratio greater than 8. For economic reasons it is desirable to use as little peroxide as is commensurate with effective desulfurization.

As previously mentioned it is desirable that the oxidation of the sulfur-containing compounds present in the oils being treated should proceed no further than sulfone formation. The conditions to achieve this end are readily known to those skilled in the art. For any given oxidant, the oxidation conditions may be varied to determine those which result in optimum sulfone formation, the presence of which may be detected by infrared analysis.

Although not essential, it is often desirable before treating a highly viscous heavy hydrocarbon oil to dissolve the oil in a low-boiling organic solvent, e.g., benzene or carbon tetrachloride; the reduction in viscosity thereby achieved enables a more thorough oxidation to take place and the overall degree of desulfurization to be improved. These solvents are well known in the art and need not be enumerated here.

The thermal after-treatment may be carried out in any manner well-known in the art, the temperature being so chosen as to minimize the degree of thermal degradation of the hydrocarbons present in the oil and being sufficient to rupture the sulfur-carbon bonds of the sulfur-containing molecules, which bonds, as mentioned above, have been weakened by the oxidation reaction. Generally temperatures in excess of 350° C. are sufficient for this purpose, i.e., about 350° C. to about 450° C. and temperatures of about 400° C. are particularly suitable. The thermal treatment may take place in the presence of alkaline materials such as dolomite or lime.

The sequence of treating steps may be repeated with advantage and thereby the sulfur content of the heavy oil reduced still further.

The present invention will be more readily understood by reference to the following examples:

EXAMPLE I

A Kuwait Long Residue, a heavy oil having a sulfur content of 4.05% by weight and formed as a residual fraction in the distillation of a Kuwait crude oil at 371° C. and atmospheric pressure, was treated in the following manner.

75 grams of the Kuwait Long Residue was dissolved in benzene and stirred at 50° C. and 28.6 milliliters of 90% by weight formic acid together with 88 milliliters of 29% w/v. hydrogen peroxide were added. Stirring was continued for seven and a half hours at 50° C. and the solvent and excess reagents were removed by distilla-

tion under reduced pressure. 15 gram samples of the product were heated for one and a half hours at 300° C., 350° C. and 400° C. yielding residual oils with sulfur contents of 3.4% w., 2.3% w. and 1.9% w. respectively. No coke formation was observed. This example shows that a very satisfactory degree of desulfurization is achieved using a molar ratio of acid/peroxide/sulfur of 8:8:1, and employing a temperature of 350° C. or 400° C. in the thermal after-treatment. The thermal treatment at 300° C., although effective to a certain extent did not result in satisfactory sulfur removal.

EXAMPLE II

In this example the same reagent ratios and conditions as in Example I were employed, but 200 grams of the Kuwait Long Residue were used and 113 grams of the oxidized product thermally treated at 400° C. This treatment produced 90% yield of a residual oil having a sulfur content of 1.9% by weight and only 0.3% by weight of coke was formed.

EXAMPLE III

100 grams of the same heavy oil as used in the above examples was dissolved in benzene and stirred for 6 hours in the presence of 176 milliliters of 29% w/v. hydrogen peroxide and 76 grams of 90% w. formic acid. After removing excess reagents and solvent, samples of the oxidized oil were heated at 350° C. and 400° C. respectively for 1½ hours, and yielded residual oils with sulfur contents of 2.74% by weight and 1.71% by weight respectively. The product from the thermal treatment at 350° C. was reoxidized using the same amount of hydrogen peroxide as in the first oxidation and a formic acid/peroxide molar ratio of 2.0. After solvent removal, the product was heated for 1½ hours at 350° C. to yield a residual oil having a sulfur content of 1.79% by weight, and this oil was heated further for 1½ hours at 400° C. to yield a residual oil having a sulfur content of 1.45% by weight.

EXAMPLE IV

In a series of experiments using a hydrogen peroxide/formic acid mixture as the oxidant, carried out to illustrate the effect of varying peroxide/sulfur molar ratio, samples of the same feedstock as was used in the previous examples were treated for 6 hours at 50° C. in the presence of benzene with formic acid and hydrogen peroxide at an acid/peroxide molar ratio of 1 and with varying peroxide/sulfur mole ratios. The products were thermally treated at 400° C. for 1½ hours and the results obtained are set out in Table I.

Table I

Mole ratio, H ₂ O ₂ /S	Thermal cracking at 400° C.			Percent S in residual oil
	Percent coke	Percent distillate	Percent residual oil	
1	2.6	10.4	73	3.88
2	2.3	12.5	69.5	3.09
4	3.8	2.3	76.7	2.25
6	5.8	15.8	65.8	1.96
8	5.8	13.6	66.9	1.67
12	5.1	15.4	65.4	1.71

These results indicate that with a formic acid/hydrogen peroxide oxidant system, the molar ratio of peroxide to sulfur should be greater than 1 and no beneficial effect is to be obtained using a mole ratio greater than 8.

EXAMPLE V

A series of experiments was carried out using the same feedstock as in the previous examples, using a formic acid/hydrogen peroxide oxidant system, in order to determine the effect on desulfurization by varying the mole ratio of formic acid to peroxide used in the oxidation step. All

the runs were carried out using a peroxide/sulfur mole ratio of 4 and oxidation was performed by treating the oil with the oxidant for 6 hours at 50° C. in the presence of benzene. The results obtained are set out below in Table II.

Table II

Mole ratio, HCOOH/H ₂ O ₂ /S	Thermal cracking at 400° C. for 1½ hours			Percent S in residual oil
	Percent coke	Percent distillate	Percent residual oil	
16:4:1	2.3	18.0	70.3	2.66
8:4:1	4.6	13.8	70.3	2.52
4:4:1	3.8	2.3	76.7	2.25
2:4:1	3.8	13.7	74.0	2.26
1.6:4:1	2.5	14.3	70.8	2.20
0.8:4:1	0.4	2.5	88.0	1.98
0.4:4:1	Nil	5.4	86.3	3.84

At higher mole ratios of acid to peroxide the by-product formation during the thermal treatment tends to increase, while at the ratios less than 1:5 the degree of desulfurization is unsatisfactory.

EXAMPLE VI

In this example, a sample of the same Kuwait Long Residue as used in the previous examples was subjected to oxidation with a formic acid/hydrogen peroxide oxidant system using a molar ratio of acid/peroxide/sulfur of 8:4:1 for 6 hours at 50° C. in the presence of benzene. 13.2 grams of the product was thermally treated in the presence of 2.7 grams of lime for 1½ hours at 400° C. A sample of the oxidation product was also cracked under the same conditions except there was no lime present. The following table illustrates the beneficial effect obtained when the thermal after-treatment is carried out in the presence of lime.

Table III

	Percent coke	Percent distillate	Percent residual oil	Percent S in residual oil
	With lime	Without lime		
	Nil	1.5	94.7	2.52
	4.6	13.8	70.3	2.03

EXAMPLE VII

In this examples a sample of reduced crude is subjected to oxidation with an acetic acid/hydrogen peroxide oxidant system using a molar ratio of acid/peroxide/sulfur of 8:4:1 at 50° C. to form sulfones without further oxidation to sulfonic acid derivatives. The oil is separated from the oxidant system and is thermally treated for 1½ hours at 400° C. The resultant heavy petroleum oil has a lower sulfur content than the feed to the process.

We claim as our invention:

1. A process for reducing the sulfur content of a sulfur-containing heavy hydrocarbon oil, at least 50% by volume of said oil boils above 250° C., which comprises treating the oil with an oxidant to form compounds containing both oxygen and sulfur, said oxygen and sulfur being chemically combined, heating the treated oil containing said compounds at a temperature from about 350° C. to about 450° C. under conditions to rupture the sulfur-carbon bond yielding volatile sulfur compounds, and recovering a heavy hydrocarbon oil of reduced sulfur content.

2. A process for reducing the sulfur content of a sulfur-containing heavy hydrocarbon oil, at least 50% by volume of said oil boils above 300° C., which comprises treating the oil with a peroxide-containing oxidant, the mol ratio of peroxide to the sulfur present being from about 1:1 to about 8:1 to form sulfones without further oxidation to sulfonic acid derivatives, heating the treated oil contain-

ing sulfones at a temperature from about 350° C. to about 450° C. under conditions to rupture the sulfur-carbon bond yielding volatile sulfur compounds, and recovering a heavy hydrocarbon oil of reduced sulfur content.

3. A process for reducing the sulfur content of a sulfur-containing heavy hydrocarbon oil, at least 90% of said oil boils above 300° C., which comprises treating the oil with a peroxide-containing oxidant consisting essentially of hydrogen peroxide and a lower alkyl monocarboxylic acid having from 1 to 2 carbon atoms, the mol ratio of peroxide to the sulfur present being from about 1:1 to about 8:8 and the mol ratio of acid to peroxide being from about 1:10 to about 4:1 to form sulfones without further oxidation to sulfonic acid derivatives, heating the treated oil containing sulfones of from about 350° C. to about 450° C. to rupture the sulfur-carbon bond yielding volatile sulfur compounds, and recovering a heavy hydrocarbon oil of reduced sulfur content.

4. A process according to claim 3 wherein the lower alkyl monocarboxylic acid is formic acid.

5. A process according to claim 3 wherein the lower alkyl monocarboxylic acid is acetic acid.

6. A process according to claim 3 wherein the sulfur-

containing heavy hydrocarbon oil is dissolved in a low boiling organic solvent before treatment.

7. A process for reducing the sulfur content of a sulfur-containing heavy hydrocarbon oil, at least 90% by volume of the oil boils above 300° C., which comprises treating the oil with a peroxide-containing oxidant consisting essentially of hydrogen peroxide and formic acid, the mol ratio of peroxide to the sulfur present being from about 1:1 to about 8:1 and the mol ratio of acid to peroxide being from about 1:1 to about 1:5, to form sulfones without further oxidation to sulfonic acid derivatives, heating the treated oil containing sulfones at about 400° C. to rupture the sulfur-carbon bond yielding volatile sulfur compounds, and recovering a heavy hydrocarbon oil of reduced sulfur content.
